UNITED STATES PATENT OFFICE.

STANLEY CZAPEK, OF DETROIT, MICHIGAN, ASSIGNOR TO RADIANT SPECIALTY COMPANY, A CORPORATION OF MICHIGAN.

DESIGN FOR A LAMP PEDESTAL.

Application filed February 25, 1926. Serial No. 16,678. Term of patent 3½ years.

To all whom it may concern:

Be it known that I, STANLEY CZAPEK, a citizen of the United States, residing at Detroit, in the county of Wayne and State of Michigan, have invented a new, original, and ornamental Design for a Lamp Pedestal, of which the following is a specification, reference being had to the accompanying drawing, forming a part hereof, and in which—

Fig. 1 is a side elevational view of the invention with the base slightly in perspective.

Fig. 2 is a fragmentary side elevational view of the obverse side of the invention showing the upper portion.

Fig. 3 is a detail plan view of the base taken on substantially line 3—3 of Fig. 1, a portion only being completed, the remaining portion being but a repetition of the completed portion.

What I claim is:

The ornamental design for a lamp pedestal, as shown.

STANLEY CZAPEK.
